COMBINED GOLF CART ACCESSORY HOLDER AND RANGE FINDER

Joseph R. Judge, 1399 Woodland Ave., Menlo Park, Calif.

Filed June 26, 1964, Ser. No. 80,601

Term of patent 14 years

(Cl. D34—5)

FIG. 1

FIG. 2

FIG. 3

FIG. 4

FIG. 1 is a top plan view of a combined golf cart accessory holder and range finder, showing my new design.

FIG. 2 is a side elevational view.

FIG. 3 is an end elevational view, and

FIG. 4 is a bottom plan view.

The dominant features of my design reside in the portions shown in full lines.

I claim:

The ornamental design for a combined golf cart accessory holder and range finder, as shown and described.
